CLAIM

The ornamental design for an ornament for spectacles as shown and described.

DESCRIPTION

FIG. 1 is a top front perspective view of the ornament for spectacles showing the claimed design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a top front perspective detail of the ornament for spectacles in an open configuration;

FIG. 9 is a top rear perspective detail of the ornament for spectacles in an open configuration; and,

FIG. 10 is an enlargement of a portion of FIG. 1.

The evenly dashed broken lines in the figures show environment and form no part of the claimed design. The unevenly dashed broken lines in FIGS. 8-10 demarcate the boundaries of those views and form no part of the claimed design.
